COMBINED CIGARETTE EXTINGUISHER AND SUPPORT

Max A. Schlatterer, Cleveland, Ohio

Application January 9, 1959, Serial No. 54,121

Term of patent 14 years

(Cl. D85—2)

Fig. 1 is a front elevational view of a combined cigarette extinguisher and support, showing my new design;

Fig. 2 is a side elevational view; and
Fig. 3 is a top plan view thereof.

I claim:

The ornamental design for a combined cigarette extinguisher and support, as shown.
